UNITED STATES PATENT OFFICE.

EDWIN H. BENNERS, OF ELIZABETH, NEW JERSEY.

SIDE FRAME FOR CAR-TRUCKS.

1,131,031.

Specification of Letters Patent.

Patented Mar. 9, 1915.

Application filed July 30, 1914. Serial No. 854,056.

To all whom it may concern:

Be it known that I, EDWIN H. BENNERS, a citizen of the United States, residing at Elizabeth, county of Union, and State of New Jersey, have invented a certain new and useful Side Frame for Car-Trucks, of which the following is a specification.

This invention is an open piece side frame for car trucks, the same being more particularly intended as an improvement upon the structure forming the subject matter of my prior Patent No. 872,790, granted December 3, 1907.

The object of the invention is to stiffen the frame by a distribution of the metal with a view to taking care of the stresses which tend to buckle or distort the structure without, however, increasing to any substantial extent the weight of the frame.

A further object is to produce a frame the length of which exceeds the linear dimensions of an ordinary frame, which longer frame involves a construction reinforced at certain places so as to withstand the stresses and at the same time is not disproportionately increased in weight.

The invention embodies a cast side frame comprising upper and lower chords and upright struts connecting said chords and forming with the same a central bolster opening and a plurality of other openings positioned at the respective sides of said central opening, said chords and struts being channel-shaped in cross section, with the channels facing inwardly and bounding the openings other than the bolster opening, and with the marginal portions of said channels provided with reentrant flanges.

The invention embodies, also, a lower chord or member of box-like cross section, said lower member or chord being provided at the top thereof with inwardly projecting or reentrant flanges overhanging the top of the chamber in said box.

The invention comprises, also, an elongated cast metal frame embodying top and bottom chords and vertical webs connecting said chords, said webs being provided in addition to the central bolster opening with a plurality of openings at each side of the bolster opening, a salient feature of the elongated frame being the employment of columns between the openings and intermediate the webs, which columns and webs are channel-shaped in cross section to afford

the required strength to resist the stresses that tend to buckle or distort the frame.

Other features and advantages of the invention will appear from the following detail description.

In the drawings, Figure 1 is a side elevation partly in vertical section of a cast metal side frame embodying the invention. Fig. 2 is a plan view thereof. Fig. 3 is a vertical cross section in the plane of the dotted line 3-3 of Fig. 1 looking in the direction of the arrow. Fig. 4 is a horizontal sectional plan view, the plane of the section being indicated by the dotted line 4-4 of Fig. 1. Fig. 5 is a transverse vertical section on the line 5-5 of Fig. 1. Fig. 6 is a side elevation partly in vertical section of a long side frame, wherein a plurality of openings are provided at each side of the central bolster opening and vertical columns are employed intermediate the side openings. Fig. 7 is a vertical cross section on the line 7-7 of Fig. 6. Fig. 8 is a horizontal section on the line 8-8 of Fig. 6. Fig. 9 is a vertical cross section on the line 9-9 of Fig. 6.

The side frame illustrated in Figs. 1 to 5, inclusive, embodies a top member A, a bottom member B, and side members C D, the latter being in the form of plates or webs connecting the top member and the bottom member. The top member and the bottom member A B constitute the top and bottom chords respectively of the frame, all the parts of which are integral, being cast in one piece. As shown, the top member A is curved in the direction of its length, the respective end portions a of said top member being inclined. For the purpose of reducing the weight, the top member is provided with openings a' separated by intervening bridge bars a². The top member and the bottom member are joined with the webs or plates C D so as to produce members channel-shaped in cross section, said channels facing inwardly. The bottom member or chord B is considerably shorter than the top member A, and at the respective ends of the frame there are provided walls or members E, the latter being inclined upwardly from the bottom member and extended to form seats e which join with the inclined extremities a so as to constitute a firm bearing for an axle box. The side members C D are provided with central openings F

- adapted to receive the usual bolster, the marginal edges of said bolster openings F being formed by columns f adapted to be slidably engaged with the bolster and to 5 perform the function of guides therefor. In addition to the bolster opening F the side members C D of the frame are provided with openings G G', the latter being positioned on opposite sides of the bolster opening. The provision of these side openings G G', reduces the weight of the metal in the side frame, but to take care of the stresses said openings are provided at the lower portion with a curved web g integral with 10 the respective side plates and connecting the latter at the lower portion of said openings G G'. The side webs C D and the inclined end members E are joined to constitute a member channel-shaped in cross section, as 15 illustrated in Fig. 5, and to further increase the rigidity and stiffness of the frame so as to preclude buckling or distortion under the stresses, I provide the reentrant flanges g', the latter extending from the respective 20 end portions of the web g so as to constitute boundaries for the marginal edges of the openings G G'. These reentrant flanges g' extend inwardly from the respective side webs, as shown in Fig. 5, and if desired 25 said reentrant flanges may extend entirely around the marginal edges of the openings, but it is preferred to cut out some of the metal on the sides of the openings next to the column guides, see Fig. 1.
- 30 The bottom member or chord B is box-shape or channelled in cross section, and said bottom member consists of a lower web b, a plurality of upstanding webs b', upwardly extending top flanges b², and inwardly extending or reentrant flanges b³, see Fig. 3. The channel or box shape of the bottom member reduces the weight of the metal in the lower part of the frame, whereas the webs and flanges composing 35 said member impart the required rigidity and stiffness to the bottom chord. The flanges b² b³ are provided with perforations adapted to receive bolts by which certain angles may be fastened to the bottom member, certain of said openings serving as 40 drain holes for the escape of water from the interior of the bottom member. The rigidity of the bottom member is increased by the addition of the reentrant flanges b³, the latter constituting distinctly novel features in the construction of the skeletonized bottom chord.
- 45 The upwardly inclined members E are shown as having lugs h extending outwardly therefrom intermediate the end portions of said members, and to these lugs are attached stays H adapted to be fastened to an axle box (not shown). It is apparent that when required suitable interposed liners 50 may be used in connection with the stays

for lining up the axle boxes as required, but as such liners constitute no part of this invention, I have not considered it necessary to illustrate the same herein.

I designate brake beam hangers fastened 70 to one of the side webs composing the frame, said hangers being positioned at the respective sides of the bolster opening and extending outwardly from the frame.

The construction illustrated in Figs. 6 75 to 9, inclusive, of the drawings embodies the salient features of the invention as heretofore described, but the frame therein illustrated is intended to be considerably longer than the frame shown in Fig. 1. It is apparent that the frame of Fig. 6 embodies the top member A, the bottom member B, the side webs C D, the inclined members E, the bolster opening F, and the side openings G G', all as hereinbefore disclosed. In 80 addition to the side openings G G' the frame is provided with other side openings J J' and columns K, K', the latter being positioned intermediate the openings G J and G' J' and between the side webs C D. 90 The openings described materially reduce the weight of the frame, whereas the columns K K' add materially to the stiffness of the frame for resisting the stresses. The columns K K' are positioned vertically 95 so as to join the top member A and the inclined end members E, and said columns K also join with the respective side members C D. The frame of Fig. 6 is provided with box stays H and with the brake beam 100 hangers I, the positions of the latter being indicated by dotted lines in Fig. 6, and the same being shown in applied positions in Fig. 7. It will be noted that the brake beam hangers are applied or attached to one of the side members opposite to or in line with the intermediate columns K K'. That is to say, said columns K K' act as vertical struts between the top and bottom chords and, further, said struts or columns carry the 105 brake beam hangers. Attention is invited to the fact that the top member A is joined with the side webs C D, which webs are provided with reentrant flanges c, constituting a channel in cross section with reentrant flanges, thereby adding materially 110 to the rigidity and stiffness of the top member without a proportionate increase in the weight of the metal.

Having thus fully described the invention, what I claim as new, and desire to secure by Letters Patent is:

1. A side frame for car trucks comprising upper and lower chords and upright struts connecting said chords and forming with the same a central bolster opening and a plurality of other openings positioned at the respective sides of said central opening, said chords and struts being channel shaped in cross section with the channels facing in 125 130

wardly and bounding the openings, said side openings being provided with reentrant flanges.

2. A side frame for car trucks comprising upper and lower chords and upright struts connecting said chords and forming with the same a central bolster opening and a plurality of other openings positioned at the respective sides of said central opening, said chords and struts being channel shaped in cross section with the channels facing inwardly and bounding the openings, and said bottom chord being box shaped in cross section and provided at the top thereof with reentrant flanges.

3. A side frame for car trucks comprising upper and lower chords and upright struts connecting said chords and forming with the same a central bolster opening and a plurality of other openings positioned at each side of the central opening, and other struts positioned intermediate the side openings and connecting the top and bottom chords, said chords and struts being channel shaped in cross section with the channels facing inwardly and bounding the openings.

4. An integral side frame for car trucks comprising upper and lower chords, side webs and a plurality of vertical struts, said side webs and vertical struts connecting said top and bottom chords and forming a central bolster opening and a plurality of other openings at each side of the central opening, said chords, webs and struts being channel shaped in cross section with the channels facing inwardly and bounding the openings, certain of said vertical struts being positioned intermediate the side openings, and said last named struts being adapt-

ed to carry the brake beam hangers.

5. An integral side frame comprising upper and lower chords and struts connecting said chords and forming therewith a central bolster opening and a plurality of side openings, said chords and struts being channel shaped in cross section with the channels facing inwardly and bounding said openings, said channel-shaped chords and struts being provided with reentrant flanges.

6. An integral side frame comprising upper and lower chords, vertical webs, vertical struts and inclined struts, said webs and vertical struts connecting said chords and said inclined struts extending upwardly from the bottom chord, said struts and webs forming with the chords a plurality of openings and being channel-shaped in cross section, certain of said channels being provided with reentrant flanges.

7. An integral side frame for car trucks comprising top and bottom chords, and vertical webs and struts connecting said chords, said webs being provided with a bolster opening and with side openings, the metal at the marginal portions of said openings

being channel-shaped in cross section and the side openings having reentrant flanges.

8. An integral side frame for car trucks comprising top and bottom chords, and vertical webs and struts connecting said chords, 70 said webs being provided with a bolster opening and with side openings, the metal at the marginal portions of said openings being channel-shaped in cross section and each side opening being bounded in part by reentrant flanges and in part by webs connecting the side webs.

9. An integral side frame for car trucks comprising top and bottom chords, and vertical webs and struts connecting said chords, 80 said webs being provided with a bolster opening and with side openings, the metal at the marginal portions of said openings being channel-shaped in cross section and said bottom chord being provided with webs 85 and flanges constituting a box-shape in cross section, certain of said flanges extending inwardly over the chamber of said box-shaped chord and other flanges extending outwardly from the webs.

10. An integral side frame for car trucks comprising top and bottom chords, and vertical webs and struts connecting said chords, said webs being provided with a bolster opening bounded by the vertical struts and provided also with other openings positioned at the respective sides of the bolster opening, certain of the vertical struts being positioned beyond the bolster opening and between adjacent side openings, said last 100 named vertical struts connecting the side webs and connecting, also, the top and bottom chords.

11. An integral side frame for car trucks comprising top and bottom chords, and vertical webs and struts connecting said chords, said webs being provided with a bolster opening bounded by the vertical struts and provided also with other openings positioned at the respective sides of the bolster opening, certain of the vertical struts being positioned beyond the bolster opening and between adjacent side openings, and brake beam hangers fastened to one vertical web substantially opposite to said intermediate 115 vertical struts.

12. A cast metal side frame embodying top, bottom, diagonal and upright members and side webs connecting said members, said side webs being provided with a central bolster opening bounded by the top, bottom and upright members and provided also with side openings bounded by said top, bottom, diagonal and upright members, said members being channel-shaped in cross section 120 and provided with reentrant flanges.

13. A side frame for car trucks comprising upper and lower chords and upright struts connecting said chords and forming with the same a central bolster opening and 130

a plurality of other openings positioned at the respective sides of said central opening, additional vertical struts positioned at the respective sides of the central bolster opening and connecting the top and bottom chords, and brake beam hangers carried by said additional vertical struts.

In testimony whereof I have signed my name to this specification in the presence of two subscribing witnesses.

EDWIN H. BENNERS.
